UNITED STATES PATENT OFFICE.

HAROLD D. MORTENSON, OF KLAMATH FALLS, OREGON.

MARKING DEVICE.

Application filed July 28, 1926. Serial No. 125,477.

This invention relates to marking devices and particularly pertains to a device for marking lumber and the like.

In the production of lumber it is a common custom for each board to be inspected and marked with a designating number by which it may be later classified. At the present time this operation is carried out by an inspector who marks on the boards with crayon. Due to the necessity for haste in inspecting the boards and the inconvenience in marking upon them while they lay upon the ground, the designating marks are not always clear and distinct, and it is the principal object of the present invention to provide a simple and compact marking device which may be carried by the inspector and may be selectively operated to stamp the classifying indicia upon the board in a legible manner and without necessitating that the inspector shall lean over or stoop down to perform the operation.

The present invention contemplates the use of a frame member carrying a plurality of independently operable self-inking stamps, said frame with its stamps being mounted on the end of a relatively long handle by which the device may be carried from place to place. The stamps may be selectively operated or a marking operation carried on without requiring that the operator need stoop down to manipulate the device or mark the boards.

The invention is illustrated by way of example in the accompanying drawing, in which:

Fig. 1 is a view in side elevation showing the complete device.

Fig. 2 is a fragmentary view in end elevation showing the structure.

Fig. 3 is a view in plan showing the structure as seen on the lines 3-3 of Fig. 2.

Fig. 4 is a horizontal section as seen on the line 4-4 of Fig. 5 and showing means for temporarily holding the actuating fingers in a desired position.

Fig. 5 is a partial sectional view showing the spring means for holding the actuating fingers in their upper position.

Fig. 6 is a view in vertical section through the chalk holder.

Referring more particularly to the drawings, 10 and 30 indicate frame plates through which are secured a plurality of self-inking stamps of common construction indicated at

11. As shown in Fig. 3 of the drawing, six of these self-inking stamps are here provided; although it will be appreciated that the number of stamps is immaterial. These stamps are each formed with end frame 60 members 12, between which members an inking pad 13 is disposed and a stamp 14 slidably mounted.

As is common in this type of marking device, the stamp 14 describes a half revolution as its stamping face moves from the face of the ink pad 13 to a position pressing against the plain surface to be marked, as for example, the board 15 shown in Fig. 1.

The stamp is actuated by a presser fork 16 which carries trunnions 17 at its ends and upon which trunnions the stamp is pivotally mounted. The trunnions slide along slots 18 formed through the end portions of frame 12. The presser fork 16 is fitted with an operating plunger 19 which moves down over the shaft 20. Interposed between the end of the shaft 20 and the plunger 19 is a spring 21 by which the fork 16 will be returned to its original non-printing position when pressure is released from the plunger 19. The plungers are adapted to be engaged by actuating fingers 22 or 23 which are rigidly secured to a sleeve 24. This sleeve is slidably mounted on a rod 25 which is secured centrally of the frame plate 30 and extends upwardly therefrom.

A handle 26 is secured to the upper end of the sleeve and by this handle the sleeve may be reciprocated on the rod or rotated therearound. A compression spring 27 is interposed between the hub of the fingers 22 and 23 and the plate 10, so that the sleeve 24 will be raised to an inoperative position when pressure is released from it.

Mounted on the frame plate 10 and around the rod 25 is a barrel ratchet structure 28 within which a spring pressed ratchet member 29 operates. The ratchet member 29 yieldably engages the serrations on the inner face of the barrel 28 so that the barrel may be readily set in a desired position with relation to the different stamped plungers. A pin 36 at the upper end of the barrel structure 28 engages a slot 37 which is movable with the fingers 22 and 23 and thus holds the fingers in cooperating relation with the several stamps as determined by the relative setting of the ratchet elements 28 and 29.

By reference to Fig. 3, it will be noted

that the fingers 22 and 23 are not disposed at 180° to each other but are disposed at substantially 120° to each other. This has been done in order that a very short rotation of the sleeve 24 will move one of the fingers out of engagement with a plunger and will allow the other finger to come into engagement with another plunger without an excessive amount of movement and without requiring that a single finger shall be used and of necessity shall be required to rotate a complete 360° in order to actuate all of the stamps grouped around the rod 25.

When it is desirable to place other indicating marks upon the board besides those which are provided on the stamps, a crayon 32 is used. This crayon is carried in a sleeve 33 and may be pressed downwardly against the action of a spring 24 by a plunger 35. The plunger is depressed by the finger 22 and this finger may be locked in its engaged position with the plunger 35 by being moved into the catch or lock member 31. The lock member 31 is rigidly mounted upon the sleeve 33 and it has an overhanging lip 38 arranged so that after the plunger 35 has been depressed by the finger 22, the finger 22 can, by a slight movement thereof to the right as viewed in Fig. 6, be placed under the lip 38 where the plunger 35 and the finger 22 will be held in the depressed position so that the crayon 32 will project outwardly beyond the plate 30, where it can be used as an ordinary marking crayon.

In operation of the present invention the structure is first assembled as shown in the drawings and the various stamps are made with desired classification marks, as for example, "1 Shop", "2 Shop", "1 and 2 Clear", "C Select", and "D Select". The inspector then takes the device and walks along the lumber to be inspected. After determining the grade of the lumber he then rests the foot plate 30 against the plain surface of the board and quickly turns the handle 26 so that one of the fingers 22 or 23 is in register with a desired plunger 19 of one of the stamping devices 11. Downward pressure is then applied to the handle 26, and this downward movement will of course be imparted to the selected plunger so that the desired classification mark will be printed upon the surface of the board.

In the event that the board is to be ripped or is to be designated by some other mark than the printed indicia of the stamps, the handle 26 is rotated until the finger 22 is above the crayon plunger 35, after which the handle 26 is pressed down until the finger 22 engages under the lip 38 of the lock member 31. This will then hold the handle rigidly and will permit the inspector to manipulate the entire structure so that the crayon 32 may be used to mark upon the board.

It will thus be seen that by the construc-

tion of marking device here shown, lumber may be rapidly inspected and clearly marked in a convenient manner by the inspector.

While I have shown the preferred form of my invention as now known to me, it is to be understood that various changes may be made in its construction without departing from the spirit of the invention as defined in the appended claims.

Having thus described my invention, what I claim and desire to secure by Letters Patent is:

1. A marking device comprising a frame structure, a relatively long handle secured to the top of said frame structure, a plurality of separate marking units carried by the frame, means for permitting rotation of the handle upon its longitudinal axis, and means carried by the handle whereby the marking units may be separately and selectively actuated.

2. A marking device comprising a frame structure, a handle rod rigidly secured to said frame structure and projecting from the top thereof, a handle sleeve mounted to rotate around said rod and to reciprocate lengthwise of said rod, a plurality of individual marking units carried by the frame, and actuating means carried by the handle sleeve whereby rotation of the sleeve will bring said actuating means in operative engagement and downward movement of the sleeve on the handle rod will cause said marking device to be actuated.

3. A marking device comprising a frame structure, a handle rod rigidly secured to said frame structure and projecting from the top thereof, a handle sleeve mounted to rotate around said rod and to reciprocate lengthwise of said rod, a plurality of individual marking units carried by the frame, actuating means carried by the handle sleeve whereby rotation of the sleeve will bring said actuating means in operative engagement and downward movement of the sleeve on the handle rod will cause said marking device to be actuated, and means for retracting the handle sleeve and actuating member when pressure thereon is released.

4. A marking device comprising a frame, a plurality of self-inking stamp units carried by the frame, a rigid handle member secured to the top of said frame, a handle sleeve mounted on the handle member and adapted to reciprocate or rotate with relation thereto, spring means normally holding said sleeve in its uppermost position with relation to the handle rod, and an actuating finger carried by the sleeve and adapted to be brought into register with a marking unit by rotation of the sleeve and to thereafter actuate said marking unit by downward pressure on the sleeve to cause it to move with relation to the handle rod.

5. A marking device comprising a frame,

a plurality of self-inking stamp units carried by the frame, a handle member secured to the top of said frame, a handle sleeve mounted on the handle member and adapted to reciprocate or rotate with relation thereto, spring means normally holding said sleeve in its uppermost position with relation to the handle rod, an actuating finger carried by the sleeve and adapted to be brought into register with a marking.

unit by rotation of the sleeve and to thereafter actuate said marking unit by downward pressure on the sleeve to cause it to move with relation to the handle rod, and a chalk holding member carried by the frame 15 and adapted to be selectively placed in an operative position where the chalk can be used by the manipulation of the member by the handle.

HAROLD D. MORTENSON.
